UNITED STATES PATENT OFFICE.

ADOLPH K. CROSS, OF DENVER, COLORADO.

CONCENTRATING APPARATUS.

SPECIFICATION forming part of Letters Patent No. 669,043, dated February 26, 1901.

Application filed August 20, 1900. Serial No. 27,363. (No model.)

To all whom it may concern:

Be it known that I, ADOLPH K. CROSS, a citizen of Germany, residing at Denver, in the county of Arapahoe and State of Colorado, have invented certain new and useful Improvements in Concentrating Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in apparatus for saving the metallic values of pulverized ore or placer material by concentration; and to this end the invention consists of the features, arrangements, and combinations hereinafter described and claimed, all 20 of which will be fully understood by reference to the accompanying drawings, in which is illustrated an embodiment thereof.

In the drawings, Figure 1 is a vertical longitudinal section taken on the line $x x$, Fig. 2. Fig. 2 is an end elevation of the apparatus viewed from a position at the left of Fig. 1. Fig. 3 is a perspective view of my improved concentrating-screen.

30 The same reference characters indicate the same parts in all the views.

Let the numeral 5 designate a suitable frame upon which is swung a trough or sluice 6. To the sides 6^a of this trough are connected 35 the lower extremities of depending rods or hangers 7, whose upper extremities are movably connected with the frame. The arrangement of the rods 7 is such as to permit a lateral oscillation of the trough through the instrumentalities of suitable mechanism. As 40 shown in the drawings, a crank-shaft 8 is journaled to one side of the frame, and rods 9 lead from cranks of this shaft to the trough, the arrangement being such that as the crank-shaft is rotated an oscillating movement is 45 imparted to the trough in a direction at right angles to its length. The trough is so hung as to give it a suitable inclination, its head or right-hand extremity (see Fig. 1) being high- 50 est. Near the lower extremity or tail of the trough an opening 6^c is formed in its bottom. In the rear of this opening is placed a part

6^d, which is oppositely inclined from the upper portion of the trough's bottom. Suitably supported in this trough is a screen 10, composed of flat longitudinal strips 10^a, interwoven with transverse strips, wires, or rods 10^b. The strips 10^a are placed in contact with each other, while the transverse strips or wires 10^b are placed some distance apart. In forming the screen any two adjacent strips 10^a are passed the one above and the other below the same transverse wire, while each strip 10^a is passed alternately above and below the transverse wires. Hence cells or depressions 65 10^d are formed in the alternate strips 10^a on the line of any wire 10^b. These cells have side openings, but no vertical outlet, since the strips 10^a are close together. As shown in the drawings, the cross-wires 10^c are fastened by bending their extremities to form hooks 10^e, which engage the outer edges of the outer strips 10^a. This screen, as shown in the drawings, forms a concentrating-table which is supported by cleats 6^f, attached to 70 the opposite sides of the table. Only one of these cleats is shown in the drawings.

When the apparatus is in use, the material to be treated is fed in the form of pulp upon the upper extremity of the screen-table from 80 a hopper 12 (see dotted lines, Fig. 1) or in any other suitable manner, while a lateral oscillation or vibratory movement is imparted to the trough or sluice at right angles to the direction of the strips 10^a of the table. Under 85 the influence of this movement the metallic values are caused to settle in the cells 10^d of the table, while the gangue is carried downwardly by the water and discharged at the tail of the table. The finer concentrates 90 pass through the side openings of the cells 10^d and thence into the bottom of the trough or sluice, from which they are discharged through the opening 6^c, while the coarser mineral values are caught in the cells. 95

It will be observed that the cross-wires 10^c of the table form riffles in the bottoms of the cells, which break the force of the current of water and facilitate the settling of the values.

Having thus described my invention, what I claim is—

In a concentrator, the combination with a suitable frame, of a table mounted thereon and composed of flat strips having their ad-

jacent side edges in contact, and separated
transverse wires or rods with which the said
strips are interwoven to form cells having
side openings, but no vertical outlet, and
5 means for imparting a vibratory movement
to the table at right angles to the length of
the longitudinal strips.

In testimony whereof I affix my signature
in presence of two witnesses.

ADOLPH K. CROSS.
